BOTTLE CAP RESHAPING DEVICE

Ray H. Essex, Fort Worth, Tex.

Application August 24, 1942, Serial No. 455,912

4 Claims. (Cl. 113—38)

This invention relates to new and useful improvements in bottle cap reshaping devices.

As is well known, metallic bottle caps or crowns have been in general use for capping bottles containing various types of beverages. These caps or crowns are originally manufactured of a particular shape which permits the usual cork seal disks to be inserted into said caps or crowns by the usual automatic machinery and also permits said caps to be applied to the bottles by the ordinary bottling equipment. The cap or crown has a crimped marginal edge portion which is, prior to insertion of the cork and application of the cap to the bottle, flared outwardly and during the capping operation, this flared, crimped edge portion is engaged around the bottle neck, being disposed below the usual annular bead on said bottle neck. Obviously, the capping operation distorts the cap or crown from its original shape and the removal of the cap or crown, when the bottle is opened by the consumer, adds further to the distortion of said cap. Also, after removal from the bottle the cap may become twisted or bent and thus, in every instance, the used cap or crown has lost its original shape, with the result that it cannot be reused until it is re-formed and returned to such original shape.

It is one object of the present invention to provide an improved device which is extremely simple in construction for accurately reshaping and straightening used metallic bottle caps or crowns so as to return said crowns to their original shape, whereby the usual cork sealing disk may be inserted by the ordinary automatic machinery and also whereby the re-formed crowns may be readily applied to bottles by the bottle capping machinery now in general use.

An important object of the invention is to provide an improved bottle cap reshaping device having means for positively centering or alining the cap within the die of said device prior to the application of pressure to said cap, whereby said cap is accurately positioned to assure that the subsequently applied pressure will press or reform the cap into its original shape.

Another object of the invention is to provide an improved cap reshaping device, of the character described, which not only accurately centers or alines the cap prior to the pressing or reshaping operation, but also has means for positively holding said cap centered during the entire pressing operation, whereby misalignment of the cap at any time during the reforming operation is prevented.

A particular object of the invention is to pro-

vide an improved device, of the character described, wherein the pressure means is readily adjustable to vary the pressure which is applied to the cap or crown during the reshaping operation; the adjustment of said means also compensating for caps of different thicknesses and material, whereby the device may be employed in reforming substantially all kinds of caps or crowns.

A further object of the invention is to provide an improved device, of the character described, wherein a single female die is arranged to co-act with a male die to reshape the cap or crown, the male die being constructed of two pieces or elements which at times function separately and at other times function as a unit, to first, accurately aline or center the cap or crown within the female die, then maintain said cap in proper position, and finally to press or reform said cap into its original shape.

Still another object of the invention is to provide an improved reshaping device, of the character described, wherein the pressure applying means may be actuated either by manual or by power means and also wherein the reforming dies may be plain to re-press the cap or crown into its original shape without destroying the usual crimping of the cap, or said dies may have co-operating recesses and projections which function to reshape the crimping during the reforming operation.

A construction designed to carry out the features of the invention will be hereinafter described, together with other features of the invention.

The invention will be more readily understood from a reading of the following specification and by reference to the accompanying drawings, wherein an example of the invention is shown, and wherein:

Figure 1 is an elevation of a cap re-shaping device, constructed in accordance with the invention.

Figure 2 is an enlarged view, partly in elevation and partly in section of the device and clearly illustrating the dies thereof.

Figure 3 is a horizontal, cross-sectional view, taken on the line 3—3 of Figure 2.

Figure 4 is an enlarged view, partly in section and partly in elevation and showing a cap placed within the female die and illustrating the movable or male die in a raised position prior to operation.

Figure 5 is a similar view showing the initial

movement and action of the movable or male die.

Figure 6 is a view similar to Figure 5 and illustrating the next step in the pressing operation,

Figure 7 is a view similar to Figures 4 to 6 and showing the final step in the pressing operation,

Figure 8 is an enlarged transverse sectional view of a bottle cap or crown which has been used and prior to being reshaped or reformed,

Figure 9 is a view similar to Figure 8 illustrating the re-shaped or re-formed cap and,

Figure 10 is a view, partly in section and partly in elevation of a modification of the dies.

In the drawings, the numeral 10 designates a body or block which is formed with a forwardly extending base portion 11 which is preferably made integral therewith. The body is provided with an outwardly directed base flange 12 whereby the device may be secured by bolts 13 to a suitable support (not shown). A vertically extending sleeve or cylinder 14 is disposed in vertical alignment with the base portion 11 and is formed integral with a web 15 which is, in turn, formed integral with the body 10 (Figure 3). The base portion 11 of the body has a recess 16 formed therein and this recess is adapted to receive a female die A, which die includes a base 17 having an upstanding annular flange 18 integral therewith. The inner upper end of the flange 18 which forms the side wall of the die is inclined or beveled at 19 and obviously, the interior of the female die A is of a predetermined shape in accordance with the shape into which the bottle cap or crown C which is insertable within said die, is to be pressed or formed. The female die A is disposed in axial alignment with the vertical cylinder 14 which is mounted thereabove.

A male die unit B is arranged to coact with the female die A and is constructed of two separate elements which cooperate with each other. The male die includes an elongate sleeve 20 which is slidable within the cylinder 14 and the lower end of this sleeve is beveled or inclined as shown at 21, such inclination being complementary to the bevel or incline 19 of the female die A.

The sleeve 20 is of greater length than the cylinder 14 so that the ends of said sleeve project outwardly beyond said cylinder, as is clearly shown in Figures 1 and 2. A solid piston 22 extends through the sleeve 20 and is capable of a limited sliding movement with respect to the sleeve. The piston is connected to the sleeve by means of a screw 23 which is threaded through the sleeve and extends radially inwardly into a recess 24 which is formed in the exterior surface of the piston. Manifestly, the sleeve and the piston may undergo relative movement with respect to each other, as limited by the length of the recess 24. Normally, as will be hereinafter explained, the screw 23 is at the lower end of the recess, with the result that the lower end of the piston 22 projects a slight distance below the lower end of the sleeve 20. The upper end of the piston 22 extends upwardly above the upper end of the sleeve 20 and is externally screw threaded as shown at 25.

The upper end of the sleeve 20 is also formed with external screw threads 26 whereby a collar 27 may be threaded thereon. The upper projecting end of the piston 22 has a similar collar 28 also threaded thereon and a coiled spring 29 which surrounds the upper projecting end of the piston is confined between the collars 27 and 28. Manifestly, the spring is constantly exerting its

pressure to force the sleeve 20 downwardly with respect to the piston 22, whereby said spring holds the parts in the position shown in Figure 2. By adjusting the collars 27 and 28, the tension on the spring 29 may be readily varied. The collars 27 and 28 may be considered to be parts of the sleeve 26 and piston 22 respectively.

For actuating the male die B formed by the sleeve 20 and the piston 22 so as to move the die vertically within the cylinder 14, a cap member 30 engages over the collar 28 which is threaded onto the piston 22 and this member is secured to said collar by screws 31 which are threaded through the cap member and which engage recesses 32 formed in the periphery of the collar 28. The cap member is formed with upwardly projecting ears 33 which receive the inner end of an actuating lever 34, said lever being pivotally secured to the ears by suitable pin 35. The lever 34 is also mounted on a pivot pin 36 which is mounted in the upper, bifurcated end of an upstanding bracket 37 which is preferably made integral with the body 10 of the device. The outer end of the lever 34 projects a considerable distance beyond the pivot pin 36 and manifestly, when the lever 34 is swung the male die B is moved through the cylinder 14. It might be noted that since the lever 34 has a direct connection through the cap member 30 and collar 28 with the inner piston 22 of the male die, a direct force is imparted to the piston and this force is transmitted through the coil spring 29 to the sleeve 20 of the male die unit.

As is well known, the usual metallic cap consists of a top portion 40 (Figure 8) having an annular flange or skirt 41. When this cap is applied to a bottle, the annular skirt or flange which has crimping 42 formed therein is engaged around the neck of the bottle so that said skirt or flange is substantially straight, or at substantially a right angle to the top portion 40 of the cap. The application of the cap or crown to the bottle naturally distorts the flange or skirt 41 from its original shape, that is, the shape which said cap had prior to its application to the bottle. The original shape of the cap or crown C is illustrated in Figure 9, the top portion 40 being substantially flat with the skirt 41 having a substantially vertical straight portion indicated at 41a and the marginal portion of said skirt or flange being flared or beveled outwardly as indicated at 42a. The cap or crown must have substantially the shape shown in Figure 9 in order that it might be handled by the usual automatic equipment which is used to insert the cork sealing disk into said cap and also so that it may be subsequently applied to a bottle with the ordinary bottle capping machinery; therefore, the problem has been to reshape the used cap to the original shape which said cap had when originally manufactured.

In the operation of the present device, the cap C which, of course, has been previously used and has been removed from a bottle, is inserted within the female die A. The cap may or may not have the usual cork sealing disk therein and as illustrated, the cork disk is removed. Because of the fact that the cap or crown C is distorted, twisted or bent, it will not fit perfectly within the female die A, with the result that when said cap or crown is placed within said die it is disposed at an angle therein. If a solid male die were forced into the female die immediately following the cap's insertion thereinto, the cap or

crown would not be properly re-formed because of its misalignment within the female die and therefore, it is essential that after the cap C is inserted into the die A, as shown in Figure 4, said cap be aligned within said die before the pressure is applied to the cap.

With the present device, after the cap is inserted within the die A, the lever 34 is swung to urge the male die unit B downwardly. As explained, the lever imparts movement to the piston 22 because of its direct connection therewith, and the sleeve 20 is moved through the spring 29 acting on the collar 27 of said sleeve. So long as there is no resistance to the movement of the sleeve 20, the spring 29, in effect, locks the piston 22 and the sleeve 20 together, whereby these parts move downwardly as a unit. As the male die unit moves downwardly, it reaches the position shown in Figure 5 and the extending or projecting lower end of the piston 22 first enters the cap C. A continued downward movement causes the inclined lower end 21 of the sleeve 20 to engage the highest point of the misaligned cap C, such point being indicated at 43 in Figure 5. After this engagement of the sleeve 20 with the edge of the cap, the continued movement of the male die unit B results in the cap C being pressed downwardly into the female die A so as to be properly centered or aligned therein. This proper alignment is of course aided by the engagement of the projecting lower end of the piston 22 within the cap C. When the cap or crown C has been properly aligned within the female die A, the engagement of the annular edge of the skirt or flange 41 of the cap with the lower end of the sleeve 20 sets up a resistance to the continued movement of the sleeve. This resistance, at this time is greater than the force of the spring 29 with the result that a continued swinging of the lever 34 will result in a movement of the inner piston 22 independently of the sleeve 20, whereby the lower end of the piston 22 further moves into the crown or cap, as illustrated in Figure 6. This independent movement of the piston is permitted by the connection between the sleeve 20 and piston 22, such connection being through the screw 23 and recess 24. At the same time, the independent movement of the piston 22 results in a compression of the spring 29, whereby the force of the spring being exerted upon the sleeve 20 is gradually increased.

When the spring 29 has been compressed sufficiently to overcome the resistance set up by the cap engaging the lower end of the sleeve 20, the sleeve and piston 22 are again moved together and as a single unit. By this time, the lower end of the piston 22 has entered the crown or cap a sufficient distance to prevent any movement or misalignment of the cap within the die. The subsequent simultaneous movement of the piston 22 and sleeve 20 results in the pressure being applied throughout the entire surface of the cap or crown, whereby said cap is re-shaped or pressed into the position shown in Figure 7. It is noted that this final movement of the male die unit is limited by the lower end of the piston 22 striking the inverted top 40 of the cap and therefore, the previous adjustment of the spring determines the pressure which the sleeve 20 will exert upon the marginal edge portion of the cap. The spring is so adjusted that the sleeve exerts sufficient pressure to flare this marginal portion but not a sufficient pressure to flatten the usual crimps in said marginal portion. Because of the fact that the dies A and B are properly

formed, it is apparent that the cap or crown is re-shaped or re-formed so that it is returned to its original shape, that is, the shape which said crown had prior to its application to a bottle.

5 After the cap or crown has been re-shaped, the operating lever 34 is swung so as to raise the male die unit B and when this occurs, the sleeve 20 will be slid downwardly relative to the piston 22 and to its original position, such movement being effected by the spring 29. Manifestly, 10 in the event that the cap or crown should tend to adhere or stick to the end of the male die upon the upstroke thereof, this sliding movement of the sleeve relative to the piston will act 15 as an automatic discharge means for removing the cap from the male die.

From the foregoing, it will be seen that an effective and simple re-shaping device is provided. The sleeve 20 and piston 22 are so connected that 20 they function either as a unit or independently of each other to provide the improved results. Upon initial movement, the sleeve and piston move together until the sleeve strikes the highest point of the misaligned cap or crown and such 25 engagement results in a proper centering or aligning of the cap within the die. Following the initial alignment of the cap within the female die, the piston 22 moves independently of the sleeve so as to enter the cap or crown a sufficient distance to maintain the same in alignment. Subsequent 30 movement results in the piston and sleeve moving as a unit to perform the pressing operation, whereby the top is properly re-shaped or reformed.

35 The spring 29 which functions to connect the piston and sleeve is readily adjustable by adjusting the collars 27 and 28 between which said spring is confined. By adjusting this spring and changing its tension, the independent movement 40 of the piston 22 with respect to the sleeve may be controlled and this makes it possible to re-shape caps of various wall thicknesses. Obviously, if the spring tension is increased, the piston 22 will undergo a more limited or shorter 45 independent movement before the sleeve 20 overcomes the resistance set up by the cap when the parts are in the position shown in Figure 6, with the result that the end of the sleeve 20 will travel a greater distance after the tension 50 of the spring overcomes the resistance of said cap and thereby caps of thinner wall thicknesses may be re-formed. If the spring tension is reduced, the piston 22 will have to travel a further 55 distance in order to compress the spring 29 to the point where the sleeve 20 may overcome the resistance set up by the cap, with the result that subsequent travel of the sleeve is reduced and caps of greater wall thicknesses may be re-shaped. This adjustment not only makes possible the re-shaping 60 of caps or crowns having different wall thicknesses but also permits a variation in the pressure applied by the sleeve, as well as permitting a used crown to be re-shaped either with or without the usual cork (not shown) mounted 65 within said cap or crown.

In Figures 1 to 7, the male and female dies A and B have been shown as substantially plain, that is, the bevel 19 of the female die and the inclination 21 of the male die sleeve 20 are shown 70 as substantially smooth. As is well known, the usual bottle cap or crown is provided with crimping around the annular skirt or flange 41 of said cap. It may be desirable to not only re-shape the cap, as illustrated in Figure 7 but it may be 75 desirable to re-form the crimps in the original

cap. In such instance, the bevel or incline 19 of the female die A is provided with a plurality of recesses 50, while the inclined surface 21 of the sleeve 20 is formed with complementary ribs or projections 51. Obviously, the ribs and recesses will provide for a recrimping of the marginal edge portion of the skirt 41 of the cap C at the same time that said cap is re-shaped by the device.

As has been explained, when the smooth surface dies are employed, the device is adjusted so that the lower end of the piston 22 strikes the top portion 40 of the cap member to limit any further downward movement of the male die prior to the time that the sleeve 20 applies sufficient pressure to press out the usual crimp in the cap member. In other words, the adjustment is such that the marginal edge portion of the skirt 41 of the cap is flared or bent outwardly but sufficient pressure is not applied to flatten out the usual crimping. It has been found that this crimping is sufficiently rigid to require considerably more pressure than would be required merely to flare the skirt portion 41 into its original shape, and it is for this reason that plain surface dies may be employed.

As hereinbefore described, the independent movement of the piston 22 with respect to the sleeve 20 during the intermediate portion of the stroke of the male die unit is controlled by the adjustment of the spring 29. However, if desired, the length of the recess 24 may be such that its co-action with the screw 23 will bring about a limitation of the independent movement of the piston or the overall length of the sleeve 20 may be varied. In either of these instances, a limitation of the independent movement of the plunger may be effected and therefore, the invention is not to be limited to controlling the adjustment of such movement by the spring 29.

The male die unit B has been illustrated as actuated by a manually operated lever 34 but obviously, this lever could be connected with a power mechanism which would automatically reciprocate the die unit B. Also, it is not essential that a mechanical actuating mechanism be employed for the unit B could be connected with an actuating mechanism operated by air or fluid pressure and it is to be understood that the invention is not to be limited to any particular means for imparting movement to the male die unit. Further, any method of automatically feeding the caps or crowns C into the female die A could be employed.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A cap reshaping device including, a base having a female cap die for receiving a deformed

cap, a support, a sleeve slidable in the support and having a die face on its lower end for engaging the flange of the cap supported by the female die, a piston slidable in the sleeve and extending above and below said sleeve, a rigid element on the piston above the sleeve, a coiled spring surrounding the piston between said sleeve and said element, a rigid member connecting the sleeve and piston for permitting a limited movement of said piston relative to said sleeve, and means connected with the rigid element of the piston for depressing said piston, whereby said spring initially moves the sleeve with the piston, then said piston is depressed relative to said sleeve when the depression of the sleeve is arrested so as to compress the spring and upon compression of said spring to a predetermined point said sleeve is depressed in unison with the piston to simultaneously reshape the cap.

2. A cap reshaping device including a female die member formed to receive a deformed cap for reshaping, a male die unit mounted for movement toward and away from said female die member, said unit including a piston and a sleeve disposed over said piston and having relative limited movement therewith and having their free ends formed with die faces cooperating with said female die member, resilient means engaging parts of the piston and sleeve and disposed so as to normally bias the latter toward a position tending to sheath the free ends of said piston, means disposed between the sleeve and piston permitting relative limited movement between the same and to positively prevent complete sheathing of the free end of the piston by the sleeve leaving a portion projecting beyond the sleeve to enter a cap positioned within the female die, and means for moving the piston, the resilient means and thereby the sleeve in unison toward and away from the female die member whereby upon an initial movement of the unit toward the female die member a deformed cap disposed within the latter will first be engaged by the projecting end of the piston so as to be aligned and centered thereby until the sleeve engages the flange of the cap and continued movement of the sleeve will then be momentarily arrested until the resilient means is compressed to a predetermined degree, whereupon the sleeve and piston will continue their unitary movement toward the female die to reshape said cap in conformity with the confronting faces of the die members.

3. A device of the character described in accordance with claim 2, in which means is provided to adjust said resilient means so as to vary the force exerted thereby.

4. A device of the character described, in accordance with claim 2, in which the piston is of a length so as to project beyond each end of the sleeve.

RAY H. ESSEX.
